UNITED STATES PATENT OFFICE.

CHRISTIAN NYGAARD, OF OSHKOSH, WISCONSIN.

CANT-HOOK.

SPECIFICATION forming part of Letters Patent No. 374,878, dated December 13, 1887.

Application filed July 27, 1887. Serial No. 245,427. (No model.)

To all whom it may concern:

Be it known that I, CHRISTIAN NYGAARD, a citizen of the United States, residing at city of Oshkosh, in the county of Winnebago and State of Wisconsin, have invented certain new and useful Improvements in Cant-Hooks; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to an improvement in cant-hooks; and it consists of a combined clip and toe-ferrule bolted together by a bolt passing through the handle.

The objects of my improvement are, first, to prevent the clip and ferrule from dropping off or slipping after the wooden handle shrinks; second, to allow either part of the combination to be reset without altering position of the other part; third, by combining to strengthen both the clip and ferrule. I attain these objects by the construction illustrated in the accompanying drawings, in which—

Figure 1 is a side view of cant-hook; Fig. 2, a bottom outside view of the combined clip and toe-ferrule separated, and Fig. 3 a sectional view lengthwise of cant-hook.

Similar letters refer to similar parts throughout the several views.

A is the toe-ferrule; B, the clip or dog-support; C, the wooden handle; E, bolt; F, nut; I, oblong slot-holes through which the bolt passes.

The ferrule and clip are both made of malleable iron. The toe-ferrule slides under the clip at K, and both are fastened by one bolt or locking-piece, E, passing through both slot-holes I and up through the handle. The nut is on the under side, as shown at F, Figs. 1 and 3, so it is not necessary to move the bolt when resetting either the clip or ferrule. The bolt passing through ferrule and clip prevents them from dropping off or slipping when the handle shrinks. After shrinkage of the handle,

either the toe-ferrule or clip can be forced farther up the handle and tightened by loosening the nut F, the oblong slot-holes I I sliding on the bolt. It is easier to adjust this combined clip and toe-ferrule to the handle than to adjust a solid socket, as the slot-holes allow the clip to be moved up until it fits the handle without altering position of toe-ferrule. In using a solid socket the handle must be made exactly the size and shape of inside of socket. This combination also renders the cant-hook lighter (of less weight) and still just as durable as where solid socket is used, because the bottom of the combination presents an iron face where the wear of the logs comes.

Therefore, what I claim as my invention, and desire to secure by Letters Patent, is—

1. In a cant-hook, the combination, with a handle having a tapered end, of a ferrule provided with a toe or stop, a clip or dog-support surrounding the taper, said ferrule and support being independently movable, whereby either may be adjusted to a secure position on the handle, and a locking-piece secured to the handle, whereby the parts may be shifted and locked.

2. In a cant-hook, the combination, with the handle, of a toe-ferrule, a clip or dog-support, the adjacent edges of the ferrule and support having overlapping parts and being relatively adjustable, and a locking-piece secured to the handle and engaging both parts, whereby they may be locked in any position of their adjustment.

3. In a cant-hook, the combination, with a handle, of a toe-ring, a clip or dog-support, the ring and support having overlapping slotted edges, and a locking-bolt secured to the handle and projecting through the slots, whereby the ring and support may be relatively shifted and locked.

In testimony whereof I affix my signature in presence of two witnesses.

CHRISTIAN NYGAARD.
